(No Model.)

R. E. SWARTZ.
MUSIC LEAF TURNER.

No. 606,252.

Patented June 28, 1898.

By his Attorneys, *Robert E. Swartz*

E. H. Stewart

THE NORRIS PETERS CO., PHOTO-LITHO., WASHINGTON, D. C.

UNITED STATES PATENT OFFICE.

ROBERT E. SWARTZ, OF CRESTON, IOWA, ASSIGNOR OF ONE-HALF TO C. F. SKIRVIN, OF SAME PLACE.

MUSIC-LEAF TURNER.

SPECIFICATION forming part of Letters Patent No. 606,252, dated June 28, 1898.

Application filed March 5, 1897. Serial No. 626,034. (No model.)

To all whom it may concern:

Be it known that I, ROBERT E. SWARTZ, a citizen of the United States, residing at Creston, in the county of Union and State of 5 Iowa, have invented a new and useful Music-Leaf Holder, of which the following is a specification.

My invention relates to music-leaf turners, and has for its object to provide a simple and 10 efficient construction and arrangement of parts whereby the leaves of a book or sheet-music may be turned consecutively with the minimum exertion upon the part of the operator, and to provide adjusting devices 15 whereby the parts of the apparatus may be arranged to suit books and sheets of different heights.

Further objects and advantages of this invention will appear in the following description, and the novel features thereof will be particularly pointed out in the appended claims.

In the drawings, Figure 1 is a front view of a leaf-turning apparatus constructed in accordance with my invention. Fig. 2 is a vertical central section of the operating devices on the line 2 2 of Fig. 1. Fig. 3 is a vertical sectional view of the operating mechanism on the line 3 3 of Fig. 2. Fig. 4 is a detail view 30 in perspective of the journals in which the turning-arms are mounted. Fig. 5 is a detail view in perspective of the hub of one of the turning-arms. Fig. 6 is a detail transverse section on the line 6 6 of Fig. 3.

Similar numerals of reference indicate corresponding parts in all the figures of the drawings.

1 designates a rack adapted to be applied to the music-rack of a piano, organ, or similar instrument or to be substituted for the rack of an orchestra music-stand or its equivalent, the same being provided at its bottom with a ledge or rest 2 for supporting the book or sheet and with clamps 3 for engaging the 45 back of a book or sheet or the leaves thereof which are not to be actuated by the turning-arms, said clamps being preferably constructed of spring-wire or its equivalent, having a tendency toward the plane of the rack. For 50 engagement with piano and organ music-

racks I preferably provide the rack 1 with an adjustable clip 4, held in the desired position by means of a thumb-nut 5. (Shown in Fig. 2.)

Mounted in a tubular bearing 6, secured 55 vertically to the center of the rack, is an operating-spindle 7, provided with an operating arm or lever 8, said arm being provided with a return-spring 9 secured at one end to the under side of the ledge or rest 2. The 60 operating arm or lever is provided with an extension 10, to bear against an intermediate portion of the spring 9 as the arm or lever is turned to operate the spindle 7 in opposition to the tension of the spring, and a stop-pin 65 11 is disposed in the path of the arm or lever to limit the return movement thereof.

Fitted for sliding adjustment upon the upper portion of the tubular bearing 6 is a sleeve 12, having a lateral slot 13, through which extends a set-screw 14, and it will be seen that by tightening this screw the sleeve may be locked at any desired vertical adjustment upon the tubular bearing. The upper end of the sleeve is constructed, as shown in detail 70 in Fig. 4, to form a series of concentric thimbles 15 and 16, constituting interior journals, and as these thimbles are split longitudinally to form open sides 15^a and 16^b it will be seen that they exert a clamping or clasping pressure upon the hubs 17 of the turning-arms 18, which are fitted therein for concentric rotation, the open sides of said thimbles facilitating the mounting of the hubs 17 within the thimbles. Furthermore, the thimbles are provided in their front sides with horizontal slots 75 15^b and 16^b, in which the turning-arms 18 swing as the hubs thereof are turned in the journals provided by the thimbles.

The means which I have devised for communicating consecutive motion to the turning-arms includes a tubular slide 19, fitted upon the spindle 7 and secured at the desired adjustment to suit that of the sleeve 12 by means of a set-screw 20 and a selecting-pawl 90 21, fulcrumed upon said slide and yieldingly held in its normal position by means of an actuating-spring 22. The lower end of this slide extends downward through the hub of the innermost turning-arm and bears upon 95 100

the bottom of the thimble in which said hub is mounted, whereby the proper relative adjustment of the slide and sleeve is determined.

Each turning-arm hub is provided with an upwardly-projecting ear 17^a, which is arranged in the path of the free end of the selecting-pawl 21, said pawl being adapted to engage the contiguous edge of said ear to impart rotary movement to the hub when the spindle 7 is actuated, and in order that the pawl may engage the outermost hub and thus communicate motion to the turning-arms consecutively said pawl is fitted with a cam 23, which slides upon the edges of the ears of the hubs, and thus swings the pawl outwardly against the tension of its actuating-spring 22 until the extremity of the pawl reaches the plane of the outermost ear. When such engagement occurs, the rotary motion of the pawl received from the turning-spindle is communicated to the turning-arm.

The tension of the light pawl-operating spring is such as to allow the pawl to yield outwardly by reason of the contact of its cam-surface 23 with the ends of the turning-arm hubs without overcoming the resistance offered by the contractile journals to the swinging movement of the arms, and this outward movement of the pawl continues until the flat end surface thereof bears squarely against the end surface of the outermost hub, when, the spring being sufficiently strong to overcome any outward motion due to centrifugal force, there will be no longer any tendency on the part of the pawl to move away from the operating-spindle, and hence the motion thereof in a path concentric with the spindle will be imparted to the outermost turning-arm hub.

It will be understood that while provision is made in the construction illustrated in the drawings for only two turning-arms this number may be increased by correspondingly increasing the number of journals with which the sleeve is fitted. The upper end of the spindle is fitted in a bearing 24 at the upper end of the rack and is engaged by a nut 25, and it is obvious that by removing said nut the spindle may be withdrawn after loosening the set-screws 14 and 20, after which the slide 19 may be removed to enable the sleeve 12 to be interchanged with another having a different number of journals.

Two important advantages are secured by the peculiar construction of the means for mounting the turning-arms, as hereinbefore described, these advantages being particularly apparent when the turning device is provided with a comparatively large number of arms. It is well known that the peculiar construction of the device causes the selecting means, consisting of the pawl 21 and attachments, to turn the arms consecutively in an unvarying order. In other words, the same arm is always operated first in the use of the device. Hence it happens that after protracted use the journals of certain of the arms are worn to a greater extent than others

owing to the fact that certain of the arms are exposed to more extended use than the others. This difference in the use makes it necessary, 70 in order to extend the life of the apparatus, to provide means for taking up the wear of the journals, and it is desirable to provide means for automatically taking up this wear. Hence I have devised the independent yielding means for frictionally engaging the hubs of the turning-arms, the contraction of said means serving to maintain a perfect bearing for each hub irrespective of the wearing of the parts, and the adjustment of either of said 80 yielding means is accomplished independently of the other means to suit the amount of wear of the particular hub which is held in place thereby. The other advantage attained by the above-mentioned specific construction resides in the fact that the provision of independent means for frictionally holding the hubs of the turning-arms in their several adjusted positions enables me to dispense with means, outside of the bearings of 90 said hubs, for preventing the movement of the selecting device from being communicated to more than one turning-arm at a time. In other words, each turning-arm is provided with its particular brake, which, consisting 95 of a contractile bearing, is located compactly, and hence is not exposed to contact with surrounding objects. Therefore the selecting-pawl acts upon each turning-arm independently of all of the remaining turning-arms, 100 and there is no possibility of communicating the motion of one turning-arm to another.

The turning-arms are fitted with the usual clasps 26 for engaging the leaves of a book or sheet to be turned, and a center holding-rod 27 is preferably attached to the sleeve 12 to lie in the center of such book or sheet.

Various changes in the form, proportion, and the minor details of construction may be resorted to without departing from the spirit 110 or sacrificing any of the advantages of this invention.

Having described my invention, what I claim is—

1. In a leaf-turning apparatus, the combination of turning-arms arranged in contiguous planes and having concentric hubs, provided with contiguous ears or projections, and yieldingly held in their normal positions to prevent accidental rotary movement, a selecting device having a pawl mounted to traverse a path concentric with the hubs of the turning-arms, and adapted to swing in a plane which radiates from the center of the hubs, said pawl being provided with contiguous cam and flat surfaces for engagement with the ears or projections of the hubs, whereby it is adapted to swing from the axis of the hubs until its flat surface engages the ear or projection of the outermost hub, and actuating devices for moving the pawl in its concentric path, substantially as specified.

2. In a leaf-turning apparatus, the combination of turning-arms arranged in contigu-

ous planes and having concentric hubs provided with contiguous ears or projections, said hubs being yieldingly held in their normal positions to prevent accidental rotary movement, a selecting device having a pawl mounted to traverse a path concentric with the hubs, and to swing in a plane radiating therefrom, said pawl being provided with cam and flat surfaces for engagement with the ears or projections of the hubs, and with a light spring to resist the outward-swinging movement of the pawl when its cam-surface engages the edges of the ears or projections, the resistance of said spring being less than the resistance of the turning-arms to rotary movement, whereby the pawl receives an outward-swinging movement to bring its flat surface in contact with the ear or projection of the outermost hub, and actuating devices for imparting rotary movement to the pawl, substantially as specified.

3. In a leaf-turning apparatus, the combination of turning-arms arranged in contiguous planes and having concentric hubs frictionally held from accidental rotary movement, and provided with contiguous ears or projections, a selecting device having a pawl, provided with a light actuating - spring, mounted to traverse a path concentric with the hubs and to swing in a plane radiating therefrom, and provided with means for selecting and engaging the ear or projection of the outermost hub, and actuating devices for imparting rotary movement to the pawl, substantially as specified.

4. In a leaf-turning apparatus, the combination of turning-arms having hubs provided with concentric friction-surfaces, a stationary spring in contact with the friction-surface of each hub, to hold the turning-arms in their several adjusted positions, and means for selecting and consecutively actuating the hubs in opposition to the holding-springs to impart swinging movement to the turning-arms, substantially as specified.

5. In a leaf-turning apparatus, the combination of concentric contractile journals, turning-arms having tubular hubs fitted in said journals and yieldingly held thereby in their adjusted positions, and means for consecutively actuating the arms to impart swinging movement thereto, substantially as specified.

6. In a leaf-turning apparatus, the combination with a spindle yieldingly held in its normal position, and means for actuating the same, of a series of interior journals concentric with said spindle, turning-arms having tubular hubs fitted in said journals and pro-

vided with ears arranged in a common plane, a slide fitted upon the spindle and provided with locking devices whereby it may be secured at the desired adjustment, a yielding pawl carried by the slide for engaging the ears of the turning-arm hubs consecutively, and means for adjusting said concentric journals longitudinally of the spindle, substantially as specified.

7. In a leaf-turning apparatus, the combination of a tubular bearing, a spindle mounted in said bearing and provided with a return-spring and an actuating-lever, a sleeve mounted upon the tubular bearing and carrying concentric interior journals, means for securing said sleeve at the desired vertical adjustment, turning-arms having their hubs fitted in said journals and provided with projecting ears arranged in a common transverse plane, a slide adjustably fitted upon the spindle, and a selecting-pawl carried by the slide for engaging the ears of the hubs, substantially as specified.

8. In a leaf-turning apparatus, the combination with a spindle mounted in fixed bearings and yieldingly held in its normal position, of interior journals arranged concentric with said spindle and means for adjusting the same parallel with the axis thereof, turning-arms having their hubs fitted in said journals and adjustable therewith, and a selecting device adjustably mounted upon the spindle and provided with means for consecutively engaging the hubs of the turning-arms, whereby the turning-arms and coöperating devices may be adjusted vertically to suit the height of the book or sheet of which the leaves are to be turned, substantially as specified.

9. In a leaf-turning apparatus, the combination with a rack, of a spindle, leaf-turning devices operatively connected with the spindle, an actuating-lever fixed to the spindle, a contractile return-spring attached at one end to the lever for yieldingly holding the spindle in its normal condition, a stop to limit the return movement of the lever, and an extension on the lever for engaging the spring at an intermediate point when the lever is actuated in opposition to the tension of the spring to bow the latter away from the plane of the spindle, substantially as specified.

In testimony that I claim the foregoing as my own I have hereto affixed my signature in the presence of two witnesses.
